(57) **CLAIM**

The ornamental design for a vehicle wheel, as shown and described.

DESCRIPTION

FIG. 1 is an elevational view of a vehicle wheel showing our new design; and,

FIG. 2 is a perspective view thereof.

The broken line showings of the circle in the center and the smaller circles are for illustrative purposes only and form no part of the claimed invention.

1 Claim, 1 Drawing Sheet

FIG. 1

FIG. 2
